United States Patent Office

Des. 225,101

Patented Nov. 14, 1972

225,101

CONTAINER FOR LIQUIDS OR THE LIKE

Giovanni Marchetti, Montecatini Terme, Italy, assignor to Bardahl Manufacturing Corporation, Seattle, Wash.

Filed Nov. 26, 1971, Ser. No. 202,714

Term of patent 14 years

Int. Cl. D9—02

U.S. Cl. D9—175

FIG. 1.

FIG. 2.

Fig. 3.

Fig. 4.

FIG. 5.

FIG. 6.

FIG. 1 is a side elevational view of a container for liquids or the like, showing my new design;

FIG. 2 is a top plan;

FIG. 3 is an elevational view showing the side opposite that seen in FIG. 1;

FIG. 4 is a bottom plan view;

FIG. 5 is an elevational view looking from the left of FIG. 1; and

FIG. 6 is an elevational view looking from the right of FIG. 1.

I claim:

The ornamental design for a container for liquids or the like, substantially as shown.
